UNITED STATES PATENT OFFICE

WILLIAM H. OLDFIELD, OF ROCHESTER, NEW YORK

BATH TRAP

Application filed September 10, 1929. Serial No. 391,665.

The object of this invention is to provide a new and improved form of bath trap.

Another object of the invention is to provide a trap that can be placed between joists 5 that are small as 6" in height, which joists would provide a correspondingly small space for the installation of the trap.

Another object of the invention is to provide a cleanout opening at the top of the 10 trap that is flush with the floor and is easily covered and uncovered so as to permit the easy cleaning of the trap.

Another object of the invention is to put the cleanout opening directly above the outlet waste opening and make it a part of the 15 outlet waste.

In the drawings:

Figure 1 is a vertical sectional view of the fitting taken on the line 1^x, 1^x of Figure 3.

20 Figure 2 is a vertical section on the line 2^x, 2^x of Fig. 1.

Figure 3 is a bottom plan view of the trap.

Figure 4 is a sectional view of the cleanout opening shown at the top of Figure 1 with 25 the nipples omitted.

In the drawings like reference numerals indicate like parts.

This invention is an improvement on the trap shown in my prior Patent 1,153,247. In 30 this case the body of the trap 1 is made of a single casting and is provided with a horizontally opening inlet opening 2 and a vertically opening outlet opening 3. Both of these openings are threaded with a female 35 thread. In this body is provided a trap 4 by which the trap is sealed by water. To the outlet opening is attached a **T Y** fitting herein called the outlet waste fitting which has a male thread at the inlet opening at the bottom 40 as indicated at 5 and a female thread at the top as indicated at 6. This **T Y** is also provided with a horizontally opening outlet as indicated at 7 which outlet opening is threaded with a female thread. In order to 45 picture the relative sizes of the opening, the inlet opening 2 is adapted to receive an 1½" pipe. The waste outlet opening 3 is 1½" net, or inside measurement. The cleanout opening is 2" inside of the nipple 8, or is 50 adapted to receive a 2" nipple. The con-

stricted opening in the outlet of the **T Y** fitting is 1½" and the female thread in the outlet opening 7 is intended to receive an 1½" pipe.

To the cleanout opening 6 a male threaded 55 nipple 8 is attached and above this a nipple 9 with a female thread is attached in which a male plug 10 is threaded. The nipple 9 has a shoulder 11 therein on which bears the plug 10 with a fibre washer between them making a tight joint therewith. The floor 12 is cut away so as to surround the nipple 9 and the opening in the floor is covered by a cap or plate 13 which is drawn tight down on the floor by the screw 14 which makes threaded 60 engagement with the plug 10.

In Figure 4 I have shown the nipples 8 and 9 omitted in which case the plug 10 is screwed directly into the threaded opening 6 of the 70 **T Y** fitting. Figure 4 shows the top of the fitting as it would be closed and finished if used between 6" joists and Figure 1 shows the fitting as it would be closed and finished if used between 8" joists or larger joists.

When it is desired to clean the trap the 75 screw 14 is taken out and the cover plate 13 is removed. The plug 10 is then screwed out and the fitting is then open so that a wire can be run down into either the body of the trap or into the outlet waste opening of the 80 trap. It will also be seen that the outlet waste opening can be turned in any direction to suit the conditions under which the installation is made without interfering with access to it from the cleanout opening. The 85 cleanout opening can be cemented tight with the surrounding floor so that no water can run through the floor down on to the plaster of the ceiling below.

As shown in Figure 1 the upright wall 90 of the **T Y** fitting that is opposite the horizontal outlet opening is curved toward the outlet opening and this curve serves to direct the flush in the direction of the outlet opening and keeps the passageway of uniform diameter so that there is no opportunity for the water to flow up, and there is, therefore, no opportunity for any solid matter to settle, but all solid matter will be carried out by the flush.

It will also be understood that the cleanout opening being placed in connection with the outlet waste opening makes it much easier to clean either the trap body or the outlet waste line. The outlet waste fitting can be turned in any direction to suit condition for installation without interfering with the cleanout opening. The cleanout opening can be cemented tight with the floor to prevent leakage. The cap has an inside plug which can be removed for cleaning either the trap body or the outlet waste opening.

I claim:

1. A bath trap having an oval shaped body with a boss on the top thereof, said boss having a vertically opening outlet and cleanout opening therein and having a female thread in said opening, a T Y fitting connected to the outlet opening with a male thread on the lower end of the fitting, said fitting having a horizontally opening outlet opening in the side thereof and a vertically opening cleanout opening in the top thereof through which the outlet opening of the trap and the fitting can be reached.
2. A bath trap having an oval shaped body with a boss on the top thereof, said boss having a vertically opening outlet and cleanout opening therein and having a female thread in said opening, a T Y fitting connected to the outlet opening with a male thread on the lower end of the fitting, said fitting having a horizontally opening outlet opening in the side thereof and a vertically opening cleanout opening in the top thereof through which the outlet opening of the trap and the fitting can be reached, a plug for closing the cleanout opening.
3. A bath trap having an oval shaped body with a boss on the top thereof, said boss having a vertically opening outlet and cleanout opening therein and having a female thread in said opening, a T Y fitting connected to the outlet opening with a male thread on the lower end of the fitting, said fitting having a horizontally opening outlet opening in the side thereof and a vertically opening cleanout opening in the top thereof through which the outlet opening of the trap and the fitting can be reached, the wall of said fitting opposite the horizontal outlet opening being curved toward the outlet opening to direct the flush in that direction.

In testimony whereof I affix my signature.

WILLIAM H. OLDFIELD.
